UNITED STATES PATENT OFFICE

WILLIAM T. BARRATT, OF BENNINGTON, VERMONT, ASSIGNOR TO CHARLES COOPER COMPANY, INC., OF BENNINGTON, VERMONT, A CORPORATION OF VERMONT

CIRCULAR KNITTING MACHINE

Application filed April 4, 1930. Serial No. 441,493.

This invention relates to improvements in knitting machines, being particularly adapted to use in connection with circular knitting machines of the class in which two cylinders are employed for knitting rib work, the same being preferably used in connection with two conical needle cylinders employing spring needles to produce a rib fabric.

The circular knitting machine of this invention is in many respects like the circular knitting machine for which application was filed by me on December 12, 1929, Serial No. 413,593 for Circular knitting machine, but differs therefrom in that the machine of this invention has in each feed not only a presser for the primary needles and means to throw it out of operative position, but also has a presser for the secondary needles and means to throw it out of operative position. The object of providing means for throwing the presser for the secondary needles out of operative position is to enable fine woolen and worsted yarns to be knitted on the machine. When the presser for the secondary needles was not thrown out of operation it necessitated a greater strain on the yarn than where the presser for the secondary needles is thrown out of operation. Cotton yarns would stand this extra strain, but fine woolen and worsted yarns would not, and therefore, the throwing out of the presser for the secondary needles became desirable and for certain classes of work necessary.

The machine of this invention also has a novel yarn guide for guiding yarn to the primary needles.

The object of the invention is to produce a machine of the character set forth for knitting striped fabric, that is, tubular fabric having stripes of any width or color extending circumferentially therearound.

To this end the machine of this invention embodies a plurality of yarn feeds, spaced apart around the needle cylinders, and each yarn feed embodying therein a single yarn guide, a presser for the primary needles, a presser for the secondary needles, a sinker wheel for the primary needles, means to cut off and clamp the yarn, and means to throw the yarn guide, the presser for the primary

needles and the presser for the secondary needles out of operative position, and means to at the same time operate the cutting and clamping mechanism.

The invention further contemplates the employment of pattern mechanism whereby any of the feeds may be caused to be thrown into or out of operation, the feeds being thrown into or out of operation by a contact member rotating synchronously with the needle cylinders and positioned to operate upon the different feeds, or thrown out of position so as not to operate upon said feeds by a contact member positioned between each adjacent pair of feeds, said last-named contact members being positioned by means of pattern mechanisms. By the mechanism hereinafter described, any one feed or any number of feeds may be selectively caused to be thrown out of operation or thrown into operation and held out of operation or in operation, whereby stripes of any width and different colors may be knitted circumferentially of the tubular knitted fabric.

To these ends the invention consists of the combination and arrangement of parts set forth in the following specification and particularly pointed out in the claims.

Referring to the drawings:

Fig. 1 is a plan view partly in section, and somewhat diagrammatic, illustrating one complete feed and the pattern mechanism.

Fig. 2 is a sectional elevation taken on the line 2—2 of Fig. 1.

Fig. 3 is a front elevation of one feed, the cylinders, their respective bed plates and running rings being broken away.

Fig. 4 is a detail plan view of one of the feed mechanisms.

Fig. 4a is a plan view of a portion of the mechanism for throwing out the presser for the secondary needles.

Fig. 5 is a detailed elevation of a portion of the mechanism for positioning the switch plate contact member, whereby the driving contact member is thrown into or out of alignment with the rotatable driven contact members.

Fig. 6 is an end elevation of the pattern

mechanism viewed in the direction of the arrow *a*, Fig. 1.

Fig. 7 is a side elevation of the pattern mechanism.

5 Fig. 8 is a front elevation of one of the primary needle operating cams.

Fig. 9 is a sectional elevation taken on line 9—9, Fig. 8.

Figs. 10, 11 and 12 are detail views illustrating the operation of the yarn guide and cutters.

Fig. 13 is a detail cross section through the yarn cutters taken on line 13—13, Fig. 10.

Fig. 14 is a sectional elevation taken on line 14—14, Fig. 1, illustrating the mechanism for throwing the presser for the secondary needles into and out of operation.

Fig. 15 is a sectional elevation similar to Fig. 14 but illustrating the presser for the secondary needles thrown out of operation.

Like numerals refer to like parts throughout the several views of the drawings.

In the drawings, 20 is the primary cylinder, 21 the primary needles and 22 the primary needle cams. The primary needle cylinder is fastened to a rotary running ring 23 rotatably mounted in a lower bed plate 24 supported upon a stationary frame. A rotary motion is imparted to the running ring 23 and the primary needle cylinder and its needles by a gear 25 fast to the lower running ring.

26 is the upper or secondary cylinder, 27 the secondary needles, 27' the secondary needle cams and 28 the upper running ring, to which the secondary cylinder is fastened. The upper running ring 28 is rotatably mounted in an upper bed plate 29 rigidly supported upon the frame of the machine and is 40 rotated by means of a gear 30 fast to the upper running ring.

An annular cap plate 31 projects over the upper face of the gear 30 and is fastened to the upper bed plate 29. The gears 25 and 30 45 mesh into pinions, not shown in the drawings, but corresponding to the pinions 42 and 53 in applicant's Patent No. 1,003,085, patented September 12, 1911, "Circular knitting machine". A vertical shaft 32, to which said 50 pinions are fastened, is driven by a pulley 33 through a shaft 34 and gearing, substantially as shown and described in said Letters Patent.

Yarn 35 is fed through guide eyes 36, Fig. 55 3, to a yarn guide 37 comprising a rocker arm 170, pivoted at 171 to a slide 50 and having guide eyes 173 and 174 through which the 60 guide eyes 35 passes into alignment with the sinkers of a sinker wheel 38 rotatably mounted upon a bracket 39, the sinker wheel being rotated by a gear 40 driven by the primary needles 21. The operation of the sinker wheel and its construction are substantially the same as that of the sinker wheel in said Letters Patent.

The beards of the primary needles are pressed by a presser bar 42, which is fastened to a rod 43 slidable in a bracket 44 fast to the lower bed plate 24. The rod 43 has an arm 45 fast thereto and slidable on a rod 46 fast to the bracket 44. Nuts 47 have screw-threaded engagement with the outer end of the rod 46 and between these nuts and the arm 45 a spiral spring 48 is interposed, acting to force the arm 45, rod 43 and presser bar 42 against the primary needles to press their beards in casting off the loops. All of this mechanism is substantially the same as described in said Letters Patent.

The beads of the secondary needles 27 are 80 pressed to cast off their loops by a rotary presser wheel 49, see Figs. 3 and 14, which is mounted and operated as hereinafter described.

The slide 50 upon which the rocker plate 85 of the rocker arm 170 is pivoted is slidably mounted in a bracket 51, see Figs. 2 and 3, the bracket 51 being fastened to the underside of the upper bed plate 29. Said slide 50 has an arm 52 projecting laterally therefrom and connected by an adjustable link 53 to a lever 54 which is pivoted at 55 to a bracket 56 fast to the upper bed plate 29. A spring 172 is connected at one end to the rocker arm 170 and at its opposite end to 95 the arm 52. The opposite end of the lever 54 to that at which the link 53 is connected, engages the under edge of a cam 57 which is fastened to a rotary contact member 58 mounted upon a stud 59 which, in turn, is fastened to the annular plate 31 and thereby is fastened to the upper bed plate 29. A spring 60 encircles the stud 59 within a recessed portion 61 formed in a hub 62 of the rotary contact member 58 and said spring 105 61 presses the contact member 58 against the underside of a head 63 of the stud 59, thus providing sufficient friction to prevent the rotary contact member 58 from spinning upon the stud 59.

To the upper face of the rotary contact member 58 are fastened four arms 64, which thus form a part of the contact member 58. An intermittent rotary motion is imparted to the rotary contact member 58 in a manner hereinafter described, and the cam 57 is thus rotated to push the inner end of the lever 54 downwardly, a spring 65 acting to hold the inner end of the lever 54 against the edge of the cam 57. The rotary contact member 58 is rotated in the direction of the arrow *d*, Fig. 4, and the cam 57 will thus push the inner end of the lever 54 downwardly raising the outer end of said lever and through the link 53 and slide 50 the yarn guide rocker arm 170 will be raised out of operative position, that is, from the position illustrated in Fig. 12 to the position illustrated in Fig. 10. In Fig. 12 the yarn is being fed to the needles in alignment with the 130

sinkers 38' of the sinker wheel 38 and between the yarn guide 37 and the needles there is positioned a stationary yarn guard 66; the operation of feeding the yarn to the primary needles by the sinkers being the same as described in said Letters Patent.

When the yarn guide 37 moves from the position illustrated in Fig. 12 to that illustrated in Fig. 10 the yarn 35 is raised out of the path of the sinkers 38' and is cut off and clamped by a movable cutter 67 coacting with a stationary cutter 68, all as set forth in said Letters Patent.

When the yarn guide 37 moves from the position illustrated in Fig. 12 to the position illustrated in Fig. 10 the upper end of the rocker arm 170 will engage the bracket 51 and the rocker arm 170 will then be tipped from the position illustrated in Fig. 12 to the position illustrated in Fig. 10, thus the lower end of the rocker arm yarn guide will be moved upwardly away from the sinkers 38' and also will be moved horizontally toward the cutters 67 and 68. Consequently the distance from the guide eye 173 in the rocker arm 170 to the cutters 67 and 68 will be made shorter than would be the case if the rocker arm 170 were not tipped, and also, the cut-off portion of the yarn will be held further away from the yarn sinkers, thus obviating any tendency of the fibers of the yarn which has been cut to catch in the sinker wheel and pull the yarn down between the sinker wheel and the sinker wheel cap, whereby the operation of the sinker wheel would be rendered inoperative. In Figs. 11 and 12 the rocker arm 170 engages a stop screw 171' on the slide 50.

The presser bar 42 is moved outwardly from engagement with the primary needles when the yarn is cut off, in order that the loops on the primary needles may not be cast off, and this movement of the presser bar 42 is accomplished by an arm 69 which is fastened to the lower end of a vertical shaft 70, the free end of the arm 69 bearing against one face of an arm 71 which is rigidly fastened to the arm 45. A rocking motion is imparted to the shaft 70 and the arm 69 by another arm 72 fast to the upper end of the shaft 70, which shaft is rotatably mounted in a bracket 73 fast to the upper bed plate 29.

A rocking motion is imparted to the arm 72 by a cam 74 which forms a part of the rotary contact member 58, so that when motion is imparted to the rotary contact member 58, the cam 74 bearing against the arm 72 will rock it, together with the shaft 70 and arm 69, and thus push the arms 71 and 45, which are in effect one piece, away from the needle cylinder, compressing the spring 48 and through the rod 43 moving the presser bar 42 out of engagement with the primary needles.

A rocking motion is imparted to the movable cutter blade 67 by a cam 75 fast to a

bracket 91 on the gear 30, so that as said gear 30 rotates the cam 75 will be brought into engagement with the lower edge 76 of a lever 77 pivoted at 78 to a bracket 79 fast to the upper bed plate. The outer end of the lever 77 is connected by an adjustable link 80 to an arm 81 fast to the movable cutter blade 67. The movable cutter blade is pivoted to a stud 82 fastened to a stationary bracket 83, so that as the lever 77 is rocked upwardly at its inner end, the cutter 67 will be rocked to close the same and cut off the yarn and clamp it to the stationary cutter 68. The cutter 67 is only operated to sever the yarn when the yarn guide has been raised to the position illustrated in Fig. 10 and the yarn is out of alignment with the sinkers and, therefore, the inner end of the lever 77 is normally held upwardly out of the path of the cam 75 by an arm 84 which has an ear 85 projecting normally beneath the inner end of the lever 77, as illustrated in Figs. 3 and 4.

The arm 84 is pivotally mounted at 86 to the upper bed plate 29. A spring 87 normally holds the arm 84 with the ear 85 projecting beneath the lever 77, but at the proper time and when it is desired to cut off the yarn, one of the arms 64 of the rotary contact members 58, see Fig. 4, engages a tooth 88 on the free end of the arm 84 and rocks it toward the right, Fig. 4, moving the ear 85 out from under the lever 77 and allowing the inner end of the lever 77 to be moved downwardly by a spring 89, thus bringing the inner end of the lever 77 into alignment with the cam 75 to be operated thereby at the proper time in the rotation of the needle cylinder and opening the cutter 67.

An intermittent rotary movement is imparted to the driven contact member 58 by a driving contact member 90, which consists of a pin slidably mounted in a bracket 91 fastened to the gear 30. The pin 90, as illustrated in Fig. 3 is in its lowermost position and when in this position will operate during the rotation of the needle cylinders and gears to impart an intermittent rotatable movement to the rotary contact member 58 with its arms 64, by reason of the pin 90 contacting with one of the arms 64 and rotating the driven contact member in the direction of the arrow *d*, Fig. 4, a quarter turn.

The driving contact member or pin 90 is raised out of alignment with the arms 64 on the driven contact member 58, or moved down into alignment with said arms by a switch plate 92 constituting a third contact member. The pin 90 is fastened to a slide 111 slidably vertically in the bracket 91 and is locked in either its upper or lower position by a spring-actuated pin 112. One of these switch plates, and the mechanism by which it is positioned to move the pin 90 up or

down, is provided between each pair of feeds and in the present embodiment of my invention it is intended to use eight feeds positioned at 1, 2, 3, 4, 5, 6, 7 and 8, Fig. 1.

5 The switch plate 92 is rocked into either of the positions illustrated in Fig. 5 by an arm 93 which is fastened to a shaft 94 mounted in a bracket 95 fast to the stationary ring 31. The switch plate 92 is fastened to 10 the inner end of the rock shaft 94. A rocking movement is imparted to the arm 93 and the rock shaft 94 and switch plate 92 by an arm 96 which is connected by a link 97 to the arm 93, and a rocking movement is imparted to the arm 96 by a shaft 98 mounted 15 in bearings 99 in a bracket 100 which is fastened to the frame 101 of the machine.

The outer end of the shaft 98 has an arm 102 fast thereto which is engaged by a 20 tern block 103 on the pattern chain 104 so as to raise the free end of the arm 102 and rock the switch plate 92 in one direction. When the block 103 has passed the outer end of the arm 102 said arm will drop and the 25 switch plate will be rocked in the opposite direction. The pattern chain 104 is driven by a pattern wheel 105 in a manner well known to those skilled in this art, and the pattern wheel has fastened thereto a ratchet 30 106 which is rotated by a pawl 107 and rotates upon a stud 108 fast to the frame of the machine. A reciprocatory motion is imparted to the pawl 107 by an arm 109, to the free end of which it is pivoted at 110.

35 The arm 109 is fastened to a rock shaft 113 mounted in a bracket 114 fast to the frame of the machine. The inner end of the rock shaft 113 has another arm 115 fast thereto and provided upon its free end with a cam 40 roll 116 adapted to be engaged by a cam 117 fast to the gear 30. The cam roll 116 is held in the path of the cam 117 by a spring 118 fast to the free end of an arm 119 which is in turn fastened to the rock shaft 113. The 45 arm 119 and therefore the arm 115 are limited as to downward movement by the arm 119 contacting with the bracket 114.

Each of the feeds 1, 2, 3, 4, 5, 6, 7 and 8 50 are positioned to be engaged by the driving contact member 90, one switch plate in advance of each feed.

120 is the switch plate for number 2 feed and is fastened to the inner end of a rock 55 shaft 126 and is operated by an arm 121, Figs. 6 and 7, which is fastened to a rock shaft 122 mounted in the bracket 100 and having fastened to the inner end thereof an arm 123 which is connected by a very fine wire or 60 other flexible member 124 to an arm 125 fast to the rock shaft 126 on a bracket 127 which is fastened to the annular cap plate 31. The wire 124 is guided to the arm 125 by posts 128 which are provided with annular grooves to 65 receive said wire 124. In this manner the

switch plate is tipped into position to raise the driving contact member 90, or to lower the same, by a block in the pattern chain 104.

In the same manner the switch plates, or 70 third contact members for the feeds 3 and 4, are operated by arms 129 and 130 fast to shafts 131 and 132 mounted to rock in the bracket 100. The shafts 131 and 132 are provided with arms 133 and 134 respectively, and these arms are connected to arms such as 75 the arms 93 and 125, which rock the switch plates or third contact members 92 and 120 respectively. The switch plates and connections to the same from the arms 129 and 130 are not shown in the drawings, but they 80 are substantially the same as the switch plates 92 and 120 and they are operated in substantially the same manner from the arms 129 and 130.

A switch plate or third contact member 85 135 for feed number 8 is rocked to engage the driving contact member 90 by an arm 136, Fig. 6, which is fastened to a rock shaft 137 mounted to rock in a bracket 138. The inner end of the rock shaft 137 has an arm 139 fastened thereto and connected by a flexible wire 140 guided by post 141 to a rocker arm 142 fast to a rock shaft 143 mounted in a bracket 144 on the ring 31. The switch plate 135 is fast to the inner end of the rock shaft 143 and is operated as hereinbefore described in relation to the switch plates 92 and 120. 90

Arms 145, 146 and 147 are fastened to shafts 148, 149 and 150 respectively, these shafts being mounted to rock in the bracket 138 and being connected to switch plates for the feeds 7, 6 and 5 respectively, in the same manner as hereinbefore described in relation to the connections to the switch plate 135. 95

The pattern chain 104 is provided with any 100 number of blocks desired. These blocks may be of different widths and positioned as may be desired with relation to the opposite edges of the pattern chain, so that any one of the switch plates may be operated to position the same in the path of the driving contact member in order to raise or lower it, or a block may be of sufficient width to raise a plurality of the pawls which operate to position the switch plates. The number of blocks and the width of the blocks on the pattern chain 104 is varied and their positions on the chain laterally and longitudinally thereof may be varied in order to throw the feeds into or out of operation as may be desired for producing stripes of different widths and different colors. 110

The presser wheel 49 for the secondary needles is rotatably mounted upon a stud 175, 125 Fig. 14, which is fastened to a slide 176 slidably mounted in a bracket 177. The bracket 177 is pivoted at 178 to a stud 179 adjustably fastened to a bracket 180 which, in turn, is fastened to the upper needle cam bracket 130

- 181 and the upper bed plate 29 by a screw 182. The slide 176 has an arm 183 fast to its outer end and projecting upwardly therefrom into slidable engagement with a stud 184 which is fastened to the bracket 177. A spring 185 encircles the stud 184 and presses at one end against the upper end of the arm 183 and at the other end against an adjustable nut 186. The spring 185 acts to move the slide 176 and the presser 49 for the secondary needles toward the needles. The presser 49 is moved away from the needles and out of operative engagement therewith by a lever 187 pivoted at 188 to the bracket 177. The upper end of a lever 189 pivoted at 190 to a bracket 191 which is fastened to the bracket 180. The upper end of the lever 189 has a right-angled bracket 192 fastened thereto by a screw 193. A screw 194, Figs. 4 and 14, has screw-threaded engagement with the bracket 192 and thus is brought into adjustable engagement with the rear end of a slide 195 slidably mounted upon a bracket 196 fast to the upper bed plate 29.
- 25 A spring 197 moves the slide 195 toward the upper cylinder 26 and a pin 198 in the slide 195 engages a cap 199 fast to the bracket 196, thus limiting the distance to which the slide 195 can be moved inwardly by the spring 197. The slide 195 is moved outwardly in order to rock the lever 189 and through the lever 187 cause the presser wheel 49 to be moved out of engagement with the secondary needles by the driving contact member 90 which, as the cylinders rotate as hereinbefore described, engages the inclined face 200 on the inner end of the slide 195 and pushes said slide outwardly until a pin 201 engages a pawl 202 and is held thereby against return movement as illustrated in Fig. 4a.
- 40 The pawl 202 is pivoted at 203 to the bracket 196 and a spring 204, fastened to the upper end of the bracket 196 by a screw 205, Fig. 14, bears against a pin 206 projecting downwardly from the pawl 202, and the said spring 204 thus tends to move the pawl 202 away from the slide 195 and the pin 201. Another spring 207, much heavier than the spring 204, is fastened to the arm 72 and bears against the pawl 202. When the parts are in the positions illustrated in Fig. 4 then the spring 207 barely touches the edge of the pawl 202, but when the arm 72 is rocked by the cam 74, as hereinbefore described, this spring 207 will be brought to bear with considerable pressure against the pawl 202 and will overcome any tendency of the spring 204 to move the pawl 202 away from the pin 201.
- 55 Thus when the driving contact member 90 rotates the cam 74 a quarter turn the arm 72 will cause the spring 207 to push against the pawl 202 and move it toward the pin 201 until the spring 204 engages the adjacent face of the bracket 196, being pushed against said
- face by the pin 206, and while in this position the driving contact pin 90 will engage the inclined face 200 of the slide 195 and push it back until the pin 201 has passed very slightly beyond the tooth 208 on the pawl 202, whereupon the pawl will snap into the position illustrated in Fig. 4a and the contact pin 90 having then passed beyond the slide 195 the spring 197 will move the slide 195 inwardly to the position illustrated in Fig. 4a. The inner end of the slide 195 at this time projects very slightly into the path of the driving contact member 90 as illustrated in Fig. 4a.
- Upon the next rotation, in which the driving contact member 90 is in its lowermost position, the cam 74 will be given another quarter rotation, as hereinbefore described, and the arm 72 will move away from the pawl 202 and the pressure of the spring 207 against said pawl will be released. Upon a further motion the driving contact member 90 will strike the tip of the inclined portion of the slide 195 and move the slide back slightly, enough so that the spring 204 acting against the pin 206 on the pawl 202 will move the pawl outwardly, and the slide 195 being released by the driving contact member 90 passing therebeyond said slide will be moved forward by the spring 197 until the stop pin 198 abuts against the cap 199. The parts will then be in the relative positions illustrated in Fig. 4 and the movement of the slide 195 inwardly from the position shown in Fig. 4a to the position shown in Fig. 4 will cause the presser 49 to be moved into contact with the secondary needles 27 through the action of the levers 189 and 187 and the slide 176 which is moved inwardly by the spring 185.
- Each feed is provided with a needle cam construction of the character illustrated in Figs. 8 and 9 and embodying therein a stationary needle cam 151 and a vertically movable needle cam 152. Both the cams 151 and 152 are supported on a bracket 153 which is fastened to the lower bed plate 24, and the cam 152 has fastened thereto a stud 154 and is slideable on a guide way 155 on the bracket 153. An arm 156 is pivoted at 157 to the bracket 153 and is drawn downwardly toward a stop 158 by a spring 159, one end of which is fastened to the free end of the arm 156, the other end being fastened to the bracket 153. The stop 158 consists of an arm which is pivoted at 160 to the bracket 153 and is locked in adjustable position by a screw 161. The movement of the cam 152 downwardly is thus limited by the stud 154 striking the stop 158. Its movement upwardly is limited by a screw 162 on the bracket 153 and in alignment with the stud 154 which is fastened to the cam 152. Thus the distance to which the cam 152 can be raised or lowered is limited by the stop screw 162 and by the stop arm 158 respectively.

The object of the construction illustrated in Figs. 8 and 9 is to hold the cam 152 down with a yielding pressure through the arm 156 and stud 154 and spring 159, and in the drawings the cam 152 is shown in its lowermost position and at this time the machine is doing the regular knitting and there is one loop on each of the primary needles and two loops on each of the secondary needles. 5 When, however, the yarn is severed, then there will be one loop on each of the primary needles and one loop on each of the secondary needles and this would bring an extra strain on the loops if the primary needles were 10 lowered to the same point as in the regular knitting. Therefore, to compensate for this condition and regulate the tension on the loops so that it will be the same in both instances, the cam 152 will move up slightly, due 15 to the tension on the loops, and through the primary needles until the stop screw 162 is engaged by the stud 154. This construction will prevent any extra strain being brought to bear upon the loops of any of the feeds when 20 the yarn is severed as hereinbefore described. 25

The one loop on each of the secondary needles is not cast off for the reason that the cam for the primary needles, illustrated in Fig. 8, draws the primary needles down just 30 far enough to cause the old loops on the secondary needles to be held below the points of the beards of the secondary needles, and when the presser acts on the secondary needles to press the beard into the eye, the old loops on 35 the secondary needles are lower than the point of the beard, and therefore, are retained on the needles, and while the secondary needle is raised into the cast-off position by its cam, this loop is safely under the beard and in the 40 head of the needle.

The general operation of the mechanism hereinbefore specifically and to some extent in general described is as follows:—Assuming a feed mechanism such as feed number 1 to be 45 operating to feed yarn to the primary needles, the parts will be in the relative positions illustrated in Figs. 2 and 3; the yarn guide 37 will be in the position illustrated in Fig. 12 and the yarn will then be fed to the primary 50 needles by the sinkers 38'; the presser bar 42 will be in position to press the beards of the primary needles 21 to cast off their old loops; the movable cutter blade 67 will be closed and in contact with the stationary cutter blade 55 68; the driving contact member 90 will be in the upper position and out of alignment with the arms 64 of the driven contact member 58.

When it is desired to sever the yarn and throw the feed number 1 out of operative 60 relation to the needles, the switch plate 92 will be rocked by the arm 102 and connecting mechanism and by a block 103 on the pattern chain from the position illustrated in dotted lines, Fig. 5, to that shown in full lines and 65 the contact pin or driving contact member 90

will engage the underside of the switch plate 92 and be pushed downwardly into its lowermost position, that is, into the position illustrated in Fig. 3.

As the driving contact member 90 rotates 70 synchronously with the needle cylinders, being mounted in the bracket 91 which is fastened to the gear 30, it follows that as the driving contact member 90 is carried forward in the direction that the cylinders are rotating, namely, in the direction of the arrows *e*, Fig. 1, the contact 90 will engage one of the arms 64 and rotate the driven contact member 58 in the direction of the arrow *d*, Fig. 4, a quarter turn, this will operate the 80 yarn guide as hereinbefore described and move it from the position illustrated in Fig. 12 to that illustrated in Fig. 10. The movable cutter blade will be opened at this time and the yarn will be drawn in between the 85 movable cutter blade 67 and the stationary cutter blade 68 by reason of the ear 85 on the arm 84 being withdrawn from under the inner end of the lever 77 when one of the arms 64 engages the tooth 88 on said arm 84. 90 The lever 77 being freed at its inner end is drawn downwardly by the spring 89, thus raising the outer end of the lever 77 and momentarily opening the movable cutter blade 67 through the link 80 and arm 81, thus allowing the yarn to be drawn in between the 95 two blades 67 and 68 when the yarn guide 37 is moved upwardly to the position illustrated in Fig. 10. As soon as this has happened the cutter blade 67 is closed by the 100 cam 75 engaging the lower edge 76 of the lever 77 and raising the same, thus depressing the link 80 and closing the movable cutter blade 67, severing the yarn and clamping it to the stationary cutter blade 105 68, and before the cam 75 passes out from beneath the lower edge 76 of the lever 77, said lever 77 is locked against downward movement at its inner end by the arm 84 which is released by the arm 64 on the driven 110 contact member passing beyond the tooth 88 on said arm 84 and allowing the spring 87 to move the ear 85 under the inner end of the lever 77. The presser bar 42 having been moved outwardly, as hereinbefore set forth, the old loops when the primary needles are moved down at this particular feed will not be cast off, but will be retained thereon.

The presser 49 having been moved outwardly, as hereinbefore set forth, the old 115 loops will be retained on the secondary needles.

The said feed No. 1 is left out of operation until any number of courses desired have been knit through another feed or feeds, and it is left out of operation by the switch plate 92 being tipped from the position shown in full lines, Fig. 5, to the position shown in dotted lines, so that as the contact pin 90 is brought around after the operation herein- 125 130

before described, whereby the feed number 1 was thrown out of operative relation with the needles, the said contact pin will engage the switch plate in the position illustrated in 5 dotted lines, Fig. 5, and will be moved upwardly so that as it passes the driven contact member 58 on feed number 1, it will not engage the arm 64 of said driven contact member. In other words, the feed number 1 10 will be left out of operation as long as may be desired.

When it is desired to throw it into operation, the third contact member or switch plate 92 will be moved into the position illustrated in Fig. 5, in full lines, and the contact pin 90 will be drawn downwardly to engage an arm 64 of the driven contact member and the inner end of the slide 195 as illustrated in Fig. 4a and the operation here- 15 before described, whereby the yarn guide and pressers and cutter were operated, will be reversed. The yarn guide will be thrown into operation, the pressers will be thrown into operation, the cutter will be opened to release the yarn and the yarn will be carried by the yarn guide first downwardly below its normal position, as illustrated in Fig. 11, thus bringing the yarn into alignment with the sinkers, whereupon it will again move 20 upwardly slightly to the position illustrated in Fig. 12 and the yarn will then be fed to the needles by the sinkers. During this latter operation the yarn guard 66 will prevent the yarn from being carried by the yarn guide 25 down below the sinkers.

It will be seen, therefore, that by employing blocks of different widths, spaced differently with relation to the edges of the pattern chain, and spaced as may be desired 40 longitudinally of the pattern chain, any desired combination may be obtained whereby stripes of different widths and of different colors may be knitted in a tubular fabric by the machine hereinbefore described.

45 In the foregoing specification and in the following claims the needle supports have been referred to as primary rotary needle cylinders and secondary rotary needle cylinders and while these so-called cylinders 50 are not from a strictly geometrical point of view cylinders, yet the term cylinders is used extensively in the art and in United States patents as designating circular rotary needle beds and, therefore, the term used 55 may be taken to indicate circular rotary needle beds.

I claim:

1. A circular spring needle rib knitting machine having, in combination, a primary 60 rotary needle cylinder, a secondary rotary needle cylinder, spring needles on each of said rotary needle cylinders, a plurality of feed mechanisms spaced apart around said cylinders to feed yarn to the primary needles, 65 each feed mechanism embodying a single

yarn guide, a sinker wheel, a presser member for the primary needles, a presser member for the secondary needles and a driven contact member, means operated by each of said driven contact members to throw its respective yarn guide and the presser member for the primary needles into or out of operative position, a driving contact member rotatable synchronously with said needle cylinders and adapted to engage and operate said driven 70 contact members for the purpose aforesaid, and mechanism operable by said driving contact member to throw the presser member for the secondary needles out of operative 75 position. 80

2. A circular spring needle rib knitting machine having, in combination, a primary rotary needle cylinder, a secondary rotary needle cylinder, spring needles on each of said rotary needle cylinders, a plurality of feed 85 mechanisms spaced apart around said cylinders to feed yarn to the primary needles, each feed mechanism embodying a single yarn guide, a sinker wheel, a presser member for the primary needles, a presser member for the secondary needles and a driven contact member, means operated by each of said driven contact members to throw its respective yarn guide and the presser member for the primary needles into or out of operative position, a driving contact member rotatable 90 synchronously with said needle cylinders and adapted to engage and operate said driven contact members for the purpose aforesaid, mechanism operable by said driving contact member to throw the presser member for the secondary needles out of operative 95 position. 100

3. A circular spring needle rib knitting machine having, in combination, a primary rotary needle cylinder, a secondary rotary needle cylinder, spring needles on each of said rotary needle cylinders, a plurality of feed mechanisms spaced apart around said cylinders to feed yarn to the primary needles, each feed mechanism embodying a single yarn 110 guide, a sinker wheel, a presser member for the primary needles, a presser member for the secondary needles, and a driven contact member, means operated by each of said driven contact members to throw its respective yarn guide and the presser member for the primary needles into or out of operative position, a driving contact member rotatable 115 synchronously with said needle cylinders and adapted to engage and operate said driven contact members for the purpose aforesaid, mechanism operable by said driving contact member to throw the presser member for the secondary needles out of operative position, and means operable by said driven contact member to lock said presser member for the secondary needles out of operative 120 position. 125

120

secondary needles out of operative position, said driving contact member and driven contact member subsequently operating to release said presser member for the secondary needles and allow it to be moved into operative position.

4. A circular spring needle rib knitting machine having, in combination, a primary rotary needle cylinder, a secondary rotary needle cylinder, spring needles on each of said rotary needle cylinders, a plurality of feed mechanisms spaced apart around said cylinders to feed yarn to the primary needles, each feed mechanism embodying a single yarn guide, a sinker wheel, a presser member for the primary needles, a presser member for the secondary needles and a driven contact member, means operated by each of said driven contact members to throw its respective yarn guide and the presser member for the primary needles into or out of operative position, a driving contact member rotatable synchronously with said needle cylinders and adapted to engage and operate said driven contact members for the purpose aforesaid, mechanism operable by said driving contact member to throw the presser member for the secondary needles out of operative position, means operable by said driven contact member to lock said presser member for the secondary needles out of operative position, said driving contact member and driven contact member subsequently operating to release said presser member for the secondary needles, and a spring operating to return said presser member for the secondary needles into operative position.

5. A circular spring needle rib knitting machine having, in combination, a primary rotary needle cylinder, a secondary rotary needle cylinder, spring needles on each of said rotary needle cylinders, a plurality of feed mechanisms spaced apart around said cylinders to feed yarn to the primary needles, each feed mechanism embodying a single yarn guide, a sinker wheel, a presser member for the primary needles, a presser member for the secondary needles and a driven contact member, means operated by each of said driven contact members to throw its respective yarn guide and the presser member for the primary needles into or out of operative position, a driving contact member rotatable synchronously with said needle cylinders and adapted to engage and operate said driven contact members for the purpose aforesaid, mechanism operable by said driving contact member to throw the presser member for the secondary needles out of operative position, and mechanism to move said driving contact member into or out of the path of said driven contact members.

6. A circular spring needle rib knitting machine having, in combination, a primary rotary needle cylinder, a secondary rotary

needle cylinder, spring needles on each of said rotary needle cylinders, a plurality of feed mechanisms spaced apart around said cylinders to feed yarn to the primary needles, each feed mechanism embodying a single yarn guide, a sinker wheel, a presser member for the primary needles, a presser member for the secondary needles and a driven contact member, means operated by each of said driven contact members to throw its respective yarn guide and the presser member for the primary needles into or out of operative position, a driving contact member rotatable synchronously with said needle cylinders and adapted to engage and operate said driven contact members for the purpose aforesaid, mechanism operable by said driving contact member to throw the presser member for the secondary needles out of operative position, and a third contact member for each feed mechanism adapted to be engaged by said driving contact member during its rotation, and the latter thereby positioned in or out of the path of said driven contact members.

7. A circular spring needle rib knitting machine having, in combination, a primary rotary needle cylinder, a secondary rotary needle cylinder, spring needles on each of said rotary needle cylinders, a plurality of feed mechanisms spaced apart around said cylinders to feed yarn to the primary needles, each feed mechanism embodying a single yarn guide, a sinker wheel, a presser member for the primary needles, a presser member for the secondary needles and a driven contact member, means operated by each of said driven contact members to throw its respective yarn guide and the presser member for the primary needles into or out of operative position, a driving contact member rotatable synchronously with said needle cylinders and adapted to engage and operate said driven contact members for the purpose aforesaid, mechanism operable by said driving contact member to throw the presser member for the secondary needles out of operative position, and a third contact member positioned between each pair of feed mechanisms respectively and adapted to be engaged by said driving contact member during its rotation, and the latter thereby positioned in or out of the path of the next succeeding driven contact member.

8. A circular spring needle rib knitting machine having, in combination, a primary rotary needle cylinder, a secondary rotary needle cylinder, spring needles on each of said rotary needle cylinders, a plurality of feed mechanisms spaced apart around said cylinders to feed yarn to the primary needles, each feed mechanism embodying a single yarn guide, a sinker wheel, a presser member for the primary needles, a presser member for the secondary needles and a driven

- contact member, means operated by each of said driven contact members to throw its respective yarn guide and the presser member for the primary needles into or out of operative position, a driving contact member rotatable synchronously with said needle cylinders and adapted to engage and operate said driven contact members for the purpose aforesaid, mechanism operable by said driving contact member to throw the presser member for the secondary needles out of operative position, a third contact member positioned between each pair of feed mechanisms respectively and adapted to be engaged by said driving contact member during its rotation and the latter thereby positioned in or out of the path of the next succeeding driven contact member, and mechanism to position each of said third contact members respectively in or out of the path of said driving contact member. 70
- 10 15 20 25 30 35 40 45 50 55 60 65 70 75 80 85 90 95 100 105 110 115 120 125 130
9. A circular spring needle rib knitting machine having, in combination, a primary rotary needle cylinder, a secondary rotary needle cylinder, spring needles on each of said rotary needle cylinders, a plurality of feed mechanisms spaced apart around said cylinders to feed yarn to the primary needles, each feed mechanism embodying a single yarn guide, a sinker wheel, a presser member for the primary needles, a presser member for the secondary needles and a driven contact member, means operated by each of said driven contact members to throw its respective yarn guide and the presser member for the primary needles into or out of operative position, a driving contact member rotatable synchronously with said needle cylinders and adapted to engage and operate said driven contact members for the purpose aforesaid, mechanism operable by said driving contact member to throw the presser member for the secondary needles out of operative position, a third contact member positioned between each pair of feed mechanisms respectively and adapted to be engaged by said driving contact member during its rotation, and the latter thereby positioned in or out of the path of the next succeeding driven contact member, and pattern mechanism to position each of said third contact members respectively in or out of the path of said driving contact member. 95
- 10 15 20 25 30 35 40 45 50 55 60 65 70 75 80 85 90 95 100 105 110 115 120 125 130
10. A circular spring needle rib knitting machine having, in combination, a primary rotary needle cylinder, a secondary rotary needle cylinder, spring needles on each of said rotary needle cylinders, a plurality of feed mechanisms spaced apart around said cylinders to feed yarn to the primary needles, each feed mechanism embodying a single yarn guide, a sinker wheel, a presser member for the primary needles, a presser member for the secondary needles and a driven contact member, means operated by each of said driven contact members to throw its respective yarn guide and the presser member for the primary needles into or out of operative position, a driving contact member rotatable synchronously with said needle cylinders and adapted to engage and operate said

driven contact members for the purpose aforesaid, mechanism operable by said driving contact member to throw the presser member for the secondary needles out of operative position, a third contact member positioned between each pair of feed mechanisms respectively and adapted to be engaged by said driving contact member during its rotation, and the latter thereby positioned in or out 5 of the path of the next succeeding driven contact member, and mechanism to selectively position each of said third contact members in or out of the path of said driving contact member.

13. A circular spring needle knitting machine having, in combination, a primary rotary needle cylinder, a secondary rotary needle cylinder, spring needles on each of said rotary needle cylinders, a plurality of 10 feed mechanisms spaced apart around said needle cylinders to feed yarn to the primary needles, each feed mechanism embodying a single yarn guide, sinker mechanism for the primary needles, needle pressing means for the primary needles, needle pressing means for the secondary needles and a rotatable driven contact member, cams on said rotatable driven contact member, means connected to said yarn guide and to the pressing 15 means for the primary needles and operable by said rotatable driven contact member cams to move said yarn guide and the pressing means for the primary needles into and out of operative position relatively to the needles, 20 and mechanism to throw the needle pressing means for the secondary needles out of operative 25 position.

14. A circular spring needle knitting machine having, in combination, a primary rotary needle cylinder, a secondary rotary needle cylinder, spring needles on each of said rotary needle cylinders, a plurality of 30 feed mechanisms spaced apart around said needle cylinders to feed yarn to the primary needles, each feed mechanism embodying a single yarn 35 guide, sinker mechanism for the primary needles, needle pressing means for the primary needles, needle pressing means for the secondary needles and a rotatable 40 driven contact member, cams on said rotatable driven contact member, means connected to said yarn guide and to the pressing means for the primary needles and operable by said rotatable driven contact members 45 to move said yarn guide and the pressing means for the primary needles into and out of operative position relatively to the needles, a driving contact member rotatable 50 synchronously with said needle cylinders and adapted to engage and impart to said rotatable driven contact members an intermittent rotary motion, and mechanism operable by said driving contact member to throw the needle pressing means for the secondary needles out of operative 55 position.

15. A circular spring needle knitting machine having, in combination, a primary rotary needle cylinder, a secondary rotary needle cylinder, spring needles on each of said rotary needle cylinders, a plurality of 60 feed mechanisms spaced apart around said needle cylinders to feed yarn to the primary needles, each feed mechanism embodying a single yarn guide, sinker mechanism for the primary needles, needle pressing means for the primary needles, needle pressing means for the secondary needles and a rotatable driven contact member, cams on said rotatable driven contact member, means connected to said yarn guide and to the pressing means for the primary needles and operable by said rotatable driven contact member cams to move said yarn guide and the pressing means for the primary needles into and out of operative position relatively to the needles, a driving contact member rotatable 65 synchronously with said needle cylinders and adapted to engage and impart to said rotatable driven contact members an intermittent rotary motion, and mechanism operable by said driving contact member to throw the needle pressing means for the secondary needles out of operative 70 position.

15. A circular spring needle knitting machine having, in combination, a primary rotary needle cylinder, a secondary rotary needle cylinder, spring needles on each of said rotary needle cylinders, a plurality of 75 feed mechanisms spaced apart around said needle cylinders to feed yarn to the primary needles, each feed mechanism embodying a single yarn guide, sinker mechanism for the primary needles, needle pressing means for the primary needles, needle pressing means for the secondary needles and a rotatable driven contact member, cams on said rotatable driven contact member, means connected to said yarn guide and to the pressing means for the primary needles and operable by said rotatable driven contact member cams to move said yarn guide and the pressing means for the primary needles into and out of operative position relatively to the needles, a driving contact member rotatable 80 synchronously with said needle cylinders and adapted to engage and impart to said rotatable driven contact members and cams an intermittent rotary motion, mechanism to move said driven contact member into or out of the path of said rotatable driven contact members, and mechanism operable by said driving contact member to throw the needle pressing means for the secondary 85 needles out of operative position.

16. A circular spring needle knitting machine having, in combination, a primary rotary needle cylinder, a secondary rotary needle cylinder, spring needles on each of said rotary needle cylinders, a plurality of feed mechanisms spaced apart around said cylinders to feed yarn to the primary needles, each feed mechanism embodying a single yarn guide, sinker mechanism for the primary needles, needle pressing means for the primary needles, needle pressing means for the secondary needles and a rotatable driven contact member, means connected to said yarn 90 guide and to said primary needle pressing means and operable by said rotatable driven contact member to move said yarn guide and the pressing means for the primary needles into and out of operative position relatively to the needles, a driving contact member rotatable 95 synchronously with said needle cylinders and adapted to engage and operate said driven contact members for the purpose aforesaid, and mechanism operable by said driving contact member to throw the needle pressing means for the secondary needles out of operative position, and a spring-actuated needle cam at each of said feeds adapted to regulate the tension on the loops of yarn which are on the needles.

17. A circular spring needle knitting machine having, in combination, a primary rotary needle cylinder, a secondary rotary needle cylinder, spring needles on each of said rotary needle cylinders, a plurality of feed 100 mechanisms spaced apart around said needle cylinders to feed yarn to the primary needles, each feed mechanism embodying a single yarn guide, sinker mechanism for the primary needles, needle pressing means for the primary needles, needle pressing means for the secondary needles and a rotatable driven contact member, cams on said rotatable driven contact member, means connected to said yarn guide and to the pressing means for the primary needles and operable by said rotatable driven contact member cams to move said yarn guide and the pressing means for the primary needles into and out of operative position relatively to the needles, a driving contact member rotatable 105 synchronously with said needle cylinders and adapted to engage and operate said driven contact members for the purpose aforesaid, and mechanism operable by said driving contact member to throw the needle pressing means for the secondary needles out of operative position, and a spring-actuated needle cam at each of said feeds adapted to regulate the tension on the loops of yarn which are on the needles.

mechanisms, spaced apart around said needle cylinders, to feed yarn to the primary needles, each feed mechanism embodying a single yarn guide, sinker mechanism, needle pressing means for the primary needles, needle pressing means for the secondary needles, a rotatable driven contact member, means connected to said yarn guide and to said pressing means for the primary needles and operable 5 by said rotatable driven contact member to move said yarn guide and the pressing means for the primary needles into and out of operative position relatively to the needles, a driving contact member rotatable synchronously 10 with said needle cylinders and adapted to engage and impart to said rotatable driven contact members an intermittent rotary motion, a yarn cutter, mechanism to operate the same including a cam rotatable synchronously 15 with said needle cylinders, and means operable by said driving contact member to render said yarn cutter mechanism operable or inoperable by said rotatable cam, and mechanism operable by said driving contact 20 member to throw the needle pressing means for the secondary needles out of operative position.

18. A circular spring needle knitting machine having, in combination, a primary rotary needle cylinder, a secondary rotary needle cylinder, spring needles on each of said needle cylinders, a presser for the primary needles, a presser for the secondary needles, a rotary driving contact member rotating 30 synchronously with said needle cylinders a driven contact member adapted to be engaged and operated by said rotary driving contact member, mechanism operated by said driven contact member to throw said 35 presser for the primary needles out of operative position, and mechanism operated by said driving contact member to throw said presser for the secondary needles out of operation.

40 45 In testimony whereof I have hereunto set my hand.

WILLIAM T. BARRATT.
